Herbert Fred D'Alo, Oakwood Hills-Cary, Ill., assignor to Abbott Laboratories, North Chicago, Ill.

Filed Mar. 6, 1975, Ser. No. 555,762

Term of patent 14 years

Int. Cl. D24—04

U.S. Cl. D83—1 F

FIG. 1 is a perspective view of a vacuum device for a flexible medical container showing my new design;

FIG. 2 is a front end view of the device shown in FIG. 1;

FIG. 3 is a rear end view of the device shown in FIG. 1;

FIG. 4 is a side view of the device illustrated in FIG. 1; and

FIG. 5 is a view similar to that of FIG. 4 showing the opposing side.

The broken lines representing the electric cord have been illustrated for illustrative purposes only.

I claim:

The ornamental design for a vacuum device for adding a flowable material to an expandable medical container, substantially as shown and described.
